UNITED STATES PATENT OFFICE.

BERNARD GOLDSTEIN, OF TORONTO, ONTARIO, CANADA.

BRACELET-LINK.

1,142,160.

Specification of Letters Patent. Patented June 3, 1915

Application filed April 10, 1914. Serial No. 831,047.

To all whom it may concern:

Be it known that I, BERNARD GOLDSTEIN, a citizen of the United States of America, and resident of the city of Toronto, county of York, Province of Ontario, in the Dominion of Canada, have invented certain new and useful Improvements in Bracelet-Links, described in the following specification and illustrated in the accompanying drawings, that form part of the same.

The principal objects of the invention are, to obviate the loss of time, expense and difficulties incident to the changing of a length of a link bracelet, to facilitate the placing and removal of the bracelet upon the arm, and to devise a form of link which may be readily clasped or unclasped either in fastening a bracelet on the arm or to remove or insert a link.

20 The principal feature of the invention consists in the novel construction of the link, whereby the connecting cross bar at one end of a link is removably secured within the end of the adjacent link and securely held 25 from accidental removal.

In the drawings, Figure 1 is a perspective view of a link constructed in accordance with this invention. Fig. 2 is a sectional elevational view of a pair of links shown 30 connected together and indicating by dotted lines the method of placing the two links together. Fig. 3 is a sectional elevational view of a pair of links showing one being entered into the other.

35 Like numerals of reference indicate corresponding parts in each figure.

Referring to the drawings, 1 is the composite link unit formed of a loop shaped link 2 and the side guide bars 3 closing the 40 sides of the loop 2.

The loop 2 in the ordinary form of bracelet link is an endless length of metal but in the present form of link, this loop member is provided with an opening 4 on the inner 45 or concaved side of the loop adjacent to one end and the metal of the inner side of the loop is turned inwardly at said opening and extends across the loop and is secured to the inner wall of the outer portion of the loop 50 forming the bar 5, the portion of the metal projecting beyond said bar forming a hook member 6.

The terminal end 7 of the hook 6 is beveled outwardly as shown. The side guide 55 members of the link are adapted to receive the edges of the loop portion 2 and are held

together by the cross bars 8 and 9 arranged at each end thereof, the cross bar 8 passing through the loop 2 back of the bar 5 and the bar 9 extending between the side members beyond the end 10 of the loop 2.

The bar 9 is a flat bar having its greatest width extending longitudinally of the link and is sufficiently thin to pass easily through the opening 4 in the underside of the looped portion of the link 2 but the greater width of the guide bar 9 is much too wide to pass through said opening so that when the end bar 9 of one link is inserted into the hook-shaped end of the adjacent loop and turned into 70 its normally substantially horizontal position it cannot slip out nor can such link be removed without turning the one member into a substantially right angular position in relation to the other so that the bar will 75 easily pass through the opening.

The cross bar 8 is provided with a stud 11 arranged intermediate of its length, said stud projecting outwardly through a hole 12 formed in the bar portion 5 of the loop 2 80 adjacent to the bottom opening and extending outwardly beyond said bar 5 and closing the opening 4. The outer end of the stud 11 is beveled outwardly in an opposite bevel to that of the end 7 of the hook so 85 that when it is desired to insert a link, the cross bar 9 will engage the beveled edges of the hook and the stud. The loop member 2 and side members 3 of the link construction inclose within the recess formed therein 90 a spiral spring 13 which engages the closed end of the loop 2 at one end and the cross bar 8 at the other end thus holding the cross bar 8 normally to its forward position with the stud 11 extending through the hole 12 95 and closing the opening 4. A very neat construction is thus produced which is very effective in use. The flat end cross bar 9 when entered into the hook end of the link remains securely held in place and cannot be removed unless the links are swung at right angles the one to the other. It cannot then be removed until the position of the loop and side members 3 of the link is altered by pulling the loop member outwardly from 105 the side members so as to draw the stud 11 into the hole 12, thus leaving room for the flat link to pass out through the opening 4.

The operation and use of this form of link is very simple and very effective. In order 110 to clasp the ends of a bracelet together or to insert a new link, it is merely necessary to

bring the meeting links together in a substantially right angular position so that the end cross bar 9 will be turned with its narrow edge to the opening 4 in the looped link 2. A slight inward pressure against the beveled end of the stud 11 causes it to recede in the hole 12 and allow the cross bar to enter, immediately springing back to position. When the cross bar is thus entered

10 the link may spring outwardly to its natural or normal position and cannot then come out or be disconnected accidentally and is as secure as any solidly riveted link.

When it is desired to unclasp the bracelet 15 or to remove a link therefrom it is merely necessary to turn the clasping links into a right angular position and by holding the side guides of the hooked link between the finger and thumb and turning the other link

20 at right angles and pulling the looped portion of the hook link slightly outward against its spring, the hook is moved so as to withdraw the stud 11 from the opening 4, thus leaving a space perfectly free for the

25 withdrawal of the cross bar 9 when the same may be withdrawn.

It will be understood from this description that the act of fastening the ends of the bracelet together or of putting in or 30 taking out a link is very simple and obviates the necessity of cutting or tampering with any portion of a link in order to remove a rivet so that a link may be displaced. The saving of time to the dealer selling a bracelet 35 let is thus very important and further he is enabled to enlarge or reduce a bracelet to any desirable size instantaneously so that the customer need not wait for any work to be done. The many other advantages obtained by this construction of a link will be 40 clearly obvious.

What I claim as my invention is:—

1. In a bracelet, a link member having a cross bar connecting the side at one end and 45 arranged in right angular relation thereto, the cross sectional width of said cross bar

being greater than its thickness and its greater cross sectional dimension being arranged substantially parallel with the length of the link, and a flat link member of loop 50 shape having a transverse opening on the inward side adjacent to one end and forming a hook adapted to receive the said cross bar of the aforesaid link member, said opening being of lesser width than the greater 55 dimension of said bar.

2. In a bracelet, a link member of loop shape having an opening on the inward side adjacent to one end and forming a hook, and a link member formed of a pair of 60 plates closing the sides of said loop and connected together at one end by a cross bar extending through said loop and at the other end by a flat cross bar adapted to enter the hook end of the adjacent link, said flat cross 65 bar having a longitudinal cross sectional dimension greater than the width of the entrance to the hook.

3. A bracelet having links, each link formed of a loop shaped inner member having a hook shaped extension, and an outer member formed of a pair of plates closing the sides of the loop and connected at one end by a cross bar extending through the loop, said cross bar having a pin projection 70 adapted to extend through a hole in the end of the loop to close the entrance to the hook, the other end of the side members being connected by a cross bar of flat cross sectional shape adapted to enter the hook end 75 of the adjacent link, the greater dimension thereof being substantially parallel with the length of the link and of greater width than the entrance to the hook.

Signed at the city of Toronto, county of 80 York, Ontario, Canada, this 26th day of March 1914.

BERNARD GOLDSTEIN.
